UNITED STATES PATENT OFFICE.

WILLIAM C. STEVENS, OF SUMMIT, NEW JERSEY.

MOTOR-CONTROLLER.

1,277,499.

Specification of Letters Patent. Patented Sept. 3, 1918.

Application filed November 30, 1914. Serial No. 874,688.

To all whom it may concern:

Be it known that I, WILLIAM C. STEVENS, a citizen of the United States, residing at Summit, in the county of Union and State of New Jersey, have invented new and useful Improvements in Motor-Controllers, of which the following is a full, clear, concise, and exact description, reference being had to the accompanying drawing, forming a part of this specification.

This invention relates to improvements in motor controllers and more particularly to controllers for decelerating electric motors operating under varying loads.

The invention has among its objects to provide simple and efficient decelerating means tending to automatically compensate for load variations and also acting to limit the rate of deceleration to insure a gradual slow-down irrespective of load conditions.

A further object is to provide simple and efficient means to limit the rate of deceleration by varying the range of effectiveness of the decelerating means in synchronism with the movement of the driven mechanism within the slow-down period.

Various other objects and advantages of the invention will hereinafter appear.

The invention will now be more specifically described in connection with the accompanying drawing, which diagrammatically illustrates one embodiment thereof. However, it should be understood that the invention may be embodied in other forms falling within the scope of the appended claims.

As illustrated, the controller is employed to regulate a compound motor 1 having an armature A, a series field winding F and a shunt field winding F'. For starting and accelerating the motor 1 there is provided a main line switch 2 and a series resistance R controllable by switches 3. It is, of course, to be understood that the switches 2 and 3 may be of any preferred type and controlled in any preferred manner and that the resistance R may be used for deceleration as well as acceleration. However, an additional decelerating resistance R' is provided to be automatically controlled, as hereinafter set forth.

The resistance R' is designed to be connected in shunt with the motor armature and to this end is provided with a suitable control switch 4 which, it may be assumed, is closed automatically at the desired time,

as for example, immediately following reinsertion of the series resistance R. Also, the shunt resistance R' is variable and provided with a suitable controlling element 5 illustrated as of the cross-head type and operable by a pilot motor 6 having an armature *a* and a shunt field winding *f*. The motor 6 is reversible to move the resistance controlling element 5 in opposite directions to decrease or increase resistance R' and is controlled by magnetic reversing switches 7 and 8 which are automatically controlled by a tachometer T, a suitable switch 9 being provided to render said magnetic switches inert when not required for use.

The tachometer T, which may be of any preferred form, is schematically illustrated as provided with a dial 10 and a needle or pointer 11 adapted to coöperate with contacts 12 and 13 on the dial to selectively control the switches 7 and 8. The tachometer mechanism is operatively connected by suitable means 14 to the driven mechanism, schematically illustrated as a gear 15, while the dial 10 is oscillatory and likewise operatively connected to the driven mechanism. The dial, however, is only designed to be moved during a limited part of the total movement of the driven mechanism and more particularly during that part of its movement corresponding to its slow-down range. In practice, such movement of the dial may be accomplished through connections of various different forms, that selected for illustration comprising a link connecting the dial with a double-acting cam 16 movable with the driven mechanism. With this arrangement the dial will be rotated in opposite directions at the commencement and completion of one revolution of the gear 15 and thus it will be assumed that the range of movement of the gear 15 required to restore the dial to normal position constitutes the range within which the gear is to be slowed down to the desired speed by the armature shunt resistance R'. The movement of the dial during deceleration corresponds in direction to that of the tachometer needle when indicating speed diminution.

Thus it will be observed that with the armature shunt resistance included in circuit the motor will be caused to slow down and under different load conditions the tachometer needle will be deflected into engagement with contacts 12 and 13, accord-

ing to the character of load variations, to increase and decrease the shunt resistance. This compensates for load variations while the movement of the dial insures a gradual deceleration irrespective of load conditions. As above stated, the dial is moved in the same direction as the needle when indicating deceleration, thereby causing one of its contacts to follow and the other to recede from said needle and in synchronism with the driven mechanisms. In consequence, if, when the armature shunt is completed the slow-down is gradual and the rate thereof does not exceed the rate of movement of the dial, then the relation between the contacts and the needle will not be disturbed. On the other hand, if the slow-down is abrupt then the needle will move faster than the dial, thereby tending to overtake the receding contact and thereafter if the rate of deceleration drops off the dial will tend to overtake the needle. This in turn will result in varying the shunt resistance in accordance with the speed of the motor and furthermore in accordance with the position of the dial whereby the net result will be a varying limit to the degree of deceleration according to the position of the driven mechanism and in consequence gradual deceleration irrespective of load conditions. It will, of course, be understood that the contacts on the dial may be adjusted according to the results desired.

In the controller illustrated it may be assumed that the needle moves clockwise as the speed of the driven mechanism increases and that the dial moves in a corresponding direction to the dotted line position upon initial movement of the driven mechanism. Then the contact 13 would be employed to direct operation of the pilot motor to exclude the armature shunt resistance for increasing the slow-down effect on the motor while the contact 12 would be employed for the opposite purpose. Under such conditions the needle would engage the contact 13 upon initial closure of the armature shunt circuit and then advance to engagement with contact 12 to decrease the slow down effect of resistance R' should the rate of slow down become excessive.

Although the circuit connections are very simple, the same will now be briefly described. The circuit of the motor 1 may be traced from line L through switch 2 when closed, by conductor 20 through the armature A, and thence through the series field winding and resistance R to line L', while a branch extends from conductor 20 by conductor 21 through the shunt field winding F' to line L'. When switch 4 is closed then a circuit is completed from the left hand terminal of the motor armature by conductor 22 through resistance R' and thence through said switch 4 to the right terminal of the

armature. Considering now the pilot motor, the field is connected by conductor 23 directly to line L and by conductor 24 to line L', whereas its armature circuit varies according to the operation of the switches 7 and 8. With switch 7 energized circuit extends from line L by conductors 25 and 26 through the down contacts 8^b of switch 8, by conductor 27 through the armature a from right to left, by conductor 28 through the up contacts 7^a of switch 7, by conductors 29 and 30 through switch 9 when closed to conductor 24 and thence to line L'. On the other hand, with switch 8 energized circuit is closed from line L by conductors 25 and 26 through the down contacts 7^b of switch 7, through the armature a from left to right and thence through the up contacts 8^a of switch 8 to line L'. The energizing circuit of switch 7 extends from line L by conductor 25 through the tachometer needle 11 and contact 13 by conductor 31 through the winding of said switch to conductor 29 and thence to line L' as already traced, while the energizing circuit of switch 8 extends through the tachometer needle and contact 12 by conductor 32 through the winding of switch 8 to conductor 29.

While for simplicity of illustration the controller has been applied to a non-reversible motor, it will be readily apparent that the same is also applicable to a reversible motor. Further, it will be apparent that the controller is applicable to alternating as well as direct current motors.

What I claim as new and desire to secure by Letters Patent is:

1. In a controller for a motor operating under varying load conditions, in combination, power operated decelerating means and control means therefor including coöperating devices, one of said devices being operable in response to motor speed variations for control of said decelerating means to compensate for load variations and the other of said devices being normally stationary and being adjustable to control the rate of deceleration.

2. In combination, a motor operating under varying load conditions, power operated decelerating means for said motor, control means for said decelerating means including coöperating devices, one of said devices being operable in response to speed variations of said motor and the other of said devices being normally stationary and means subjecting the latter device to adjustment by said motor whereby said devices co-operate to effect deceleration of said motor at a substantially uniform rate under varying load conditions.

3. In combination, a motor having an armature shunt resistance, governing means therefor to vary the effect thereof, said means including coöperating members, one

to move in synchronism with the motor and the other to move in response to variations in the speed of said motor, said first mentioned member having means associated therewith to limit the movement thereof to a predetermined part of the range of operation of said motor.

4. In combination, a motor, a shunt resistance and a series resistance for the circuit thereof, means for varying the resistance of said shunt to decelerate said motor, coöperating controlling members therefor to vary the effect thereof, one of said members being movable in response to variations in the speed of said motor to compensate for the effect of load variations, and means for subjecting the other of said members to movement by said motor to establish a maximum rate of deceleration irrespective of load conditions.

5. In combination, a motor, speed regulating means therefor, relatively movable coöperating members controlling said means to vary the effect thereof, one of said members comprising a speed indicator for the motor and means including a part driven by the motor for establishing and interrupting a drive between the other of said controlling members and the motor according to the position of said part, said drive when established insuring operation of said member in synchronism with the motor. 20 25 30

In witness whereof, I have hereunto subscribed my name in the presence of two witnesses.
